124,406

DESIGN FOR A STOCKING OR SIMILAR ARTICLE

Arthur O. Hanisch, Altadena, Calif., assignor to Infants Socks, Inc., Reading, Pa., a corporation of Delaware

Application September 23, 1939, Serial No. 87,360

Term of patent 7 years

To all whom it may concern:

Be it known that I, Arthur O. Hanisch, a citizen of the United States, residing at Altadena, county of Los Angeles, and State of California, have invented a new, original, and ornamental Design for a Stocking or Similar Article, of which the following is a specification, reference being had to the accompanying drawing, forming part thereof.

The figure is a side view of a stocking or similar article, showing my new design, the opposite side being of the same design.

The characterizing feature of the design resides in a stocking having a cuff portion which is ornamented with substantially uniformly spaced rows of fringe.

I claim:

The ornamental design for a stocking or similar article, substantially as shown and described.

ARTHUR O. HANISCH.
